UNITED STATES PATENT OFFICE.

JAMES E. STEPHENSON, OF ROCHESTER, NEW YORK, ASSIGNOR TO GENERAL RAILWAY SIGNAL COMPANY, OF GATES, NEW YORK, A CORPORATION OF NEW YORK.

ELECTRIC LOCK.

Application filed June 25, 1921. Serial No. 480,338.

To all whom it may concern:

Be it known that I, JAMES E. STEPHENSON, a citizen of the United States of America, residing at Rochester, in the county of Monroe and State of New York, have invented 5 certain new and useful Improvements in Electric Locks, of which the following is a specification.

This invention relates to an electrically 10 operated lock for the levers of mechanical interlocking machines of the type employing so-called lever locking, that is, that type in which the movement of the levers themselves operate the tappet bars of the mechanical interlocking between the levers.

Among the objects of the present invention are to provide a simple and compact design of an electrically operable lever lock which is strong enough to lock the lever 20 directly, which includes a circuit controller operated in accordance with the movement of the lever so that it may be used to select signal circuits or govern the operation of power operated switches and the like, in 25 which the locking parts are forced into engagement after each release, and which possesses various other desirable features and characteristics of devices of this character.

A further object of the invention is to 30 provide a construction of a lever lock which can be readily converted or adapted for use as a track circuit controlled lock for locking the lever in either the full normal or full reverse position, or both, or as an indication lock, or as a combined indication and track circuit controlled lock.

Other specific objects and advantages of 35 the invention will appear hereinafter as the description progresses.

In describing the invention in detail, reference will be made to the accompanying drawings, in which:—

Figure 1 shows one lever of a well-known 40 type of a mechanical interlocking machine, and illustrates the way in which the electric lock embodying my invention may be connected to said lever;

Fig. 2 is a fragmentary diagrammatic view partly in perspective illustrating the 45 principal parts of the lock, and its manner of connection when controlled by a track circuit;

Fig. 3 is a vertical longitudinal section 50 through the device, some parts being shown in elevation for clearness;

Fig. 4 is a horizontal section of the device taken on the line 4—4 in Fig. 3;

Figs. 5, 6, 7 and 8 are vertical transverse sections taken on the lines 5—5, 6—6, 7—7 and 8—8 respectively, of Fig. 3;

Figs. 9 and 10 show in elevation and plan respectively, an alternative form of the lock releasing electro-magnet;

Fig. 11 is a fragmentary view of the locking plunger provided with a modified form 65 of dog and guide cam;

Fig. 12 is a detail section of the modified dog shown in Fig. 11;

Fig. 13 is a cross-sectional view taken on the line 13—13 of Fig. 12, viewed in the 70 direction of the arrows;

Fig. 14 is a fragmentary view of the locking plunger provided with another modified form of guide cam;

Fig. 15 shows the device illustrated in Fig. 75 14 in the unlocked position; and

Fig. 16 is a diagrammatic view, partly in perspective, showing how the electric lock may be used, both as a track circuit controlled lock and as an indication lock.

The electric lock employing the invention is particularly designed for direct connection to the lever of a mechanical interlocking machine of the type employing lever locking. In Fig. 1, I have shown a single 80 lever L of a well known type of mechanical interlocking machine, commonly known as the McKenzie and Holland machine, and have illustrated one typical application of the lock embodying this invention to this lever. The lever L is mounted on a shaft 1 running the length of the machine and supported by the usual upright standards 2 bolted to the base timbers. The switch, fac-

ing point lock, switch and lock movement, signal, or derail, as the case may be, is connected by a suitable pipe line, wires, or the like (not shown) to the tail piece 3 of the lever. The lever L is provided with the usual latch 4 operated by a handle 5 and 85 engaging shoulders in the quadrant 6. The locking bed 7 is supported on a bracket 8,

and the tappet 9 operated by the lever L is pivotally connected to the lower end of a cam lever 10 which is journaled on a shaft 100 90 running lengthwise of the machine. The upper end of the cam lever 10 is formed with a slot 12 of general Z-shape as shown, and guided in this slot is a die or stud 13 fixed

to the lever L.

105

110

When the lever L is shifted from the normal position shown in Fig. 1, during the first part of its movement, the die 13 on the lever carries with it the upper end of the cam lever 10, raising this upper end and shifting the tappet 9 to the left. This movement of the tappet 9 causes the primary locking of all conflicting levers in the well known manner. As the lever is moved further, the die 13 slides out of the end portion of the Z-slot 12, and during the next part of the movement of the lever, the said die slides in the curved part of the Z-slot without rocking the cam lever 10. When the lever L is near the reverse position, the die 13 engages the other end of the Z-slot 12 in the cam lever 10, raising the upper end of this cam lever still further and making the final unlocking movement of the tappet 9. During movement of the lever, from the reverse position back to the normal position shown in Fig. 1, the same movement of parts occurs, and the tappet 9 is moved by successive step to the right back to the position shown.

The electric lever lock embodying the invention may be directly connected to the lever in any suitable or convenient manner, the lock itself being supported horizontally, vertically, or in an inclined position as found most expedient. In the particular arrangement illustrated in Fig. 1, the lock is mounted on suitable floor beams 14 above the locking bed 7, and is connected to an intermediate point of the lever by a rod 15. The lock, however, may be mounted vertically and connected to the tail piece 3 of the lever, or may be operatively connected to the lever in any other suitable way in such a manner that it constrains movement of the lever at the desired points in its stroke.

The lock comprises in general a main frame or casing F formed of counter-part side plates 16 which have integral therewith base portions and which are bolted together by suitable bolts 17, as shown in Fig. 5. These side plates 16, when bolted together, form a longitudinal guiding slot in which is slidably mounted a locking plunger P. The intermediate portion of this locking plunger P is provided with a cut-away portion into which a dog 18 is counter-sunk, and fastened thereto by machine screws on other suitable fastening means. Fastened to the locking plunger P directly over the dog is a guide cam 19 having the inside edges beveled or inclined as shown so as to force a lock bolt, to be described hereinafter, into locked position. On each side of the locking plunger P the side plates 16 are provided with recesses in which is guided a U-shaped lock bolt B straddling the locking plunger and positioned under the guide cam or retainer 19. This bolt B when down prevents the locking plunger P from moving farther than to the dog 18 mounted thereon.

The lock bolt B is raised by a double angle lever 20 made of one piece and pivotally supported on pins 21 secured to the side plates 16, (Fig. 10). The two long arms of this angle lever 20 are positioned over the locking plunger P and are pivoted to the U-shaped lock bolt B by a pin and slot connection. The two short arms of the double angle lever 20 extend upward and have pivotally connected thereto links 22 which have their opposite end connected to cranks 23 mounted on the ends of a shaft 24 of the lock releasing magnet M. This shaft 24 is suitably supported in bearings formed in the two halves of a housing 25 (Fig. 4) fastened together by bolts 26; and fastened to this shaft is a laminated Z-shaped armature 27. A U-shaped laminated core 28 of the usual construction, provided with inwardly extending pole pieces 28^a, is clamped between the two halves of the housing 25, so that the Z-shaped armature 27 is positioned between the poles. These pole pieces 28^a are provided with coils 29, and when these coils are energized, the armature 27 is drawn into a horizontal position, thereby raising the lock bolt B from engagement with the dog 18 on the locking plunger P. The core 28, coils 29 and Z-armature 27 constitute in effect an electro-responsive device for releasing the lock bolt B, and this device may be conveniently termed the lock releasing magnet M. The construction shown and described is adaptable for efficient operation by alternating current, being designed to obviate vibration and other objectionable effects incident to the use of alternating current for a tractive type device.

For the purpose of automatically closing the energized circuit for the lock releasing magnet M at the time a release is desired, an energy saving or cut-out switch device ES operated by the lock plunger is provided. This switch comprises a block 30 of insulating material supported on the back end of the housing 25 of the lock releasing magnet M; a fixed spring contact 31 fastened to the under side of said block 30 at one end by a suitable binding post; and a movable resilient contact member 32 fastened to the other end of said block in the same way and arranged to engage the fixed contact 31. An insulating pin 33 arranged to engage the movable contact member 32 and push the same in engagement with the fixed contact 31, is supported on the end of an operating lever 34, which has its other end pivotally supported on a pin 35 fastened in side plates of the main frame or casing F. This operating lever comprises two parallel side portions having downwardly extending ears 36 in which is pivotally mounted a roller 37. The roller 37 rides on the top of the locking plunger P, and the upper

face of the locking plunger P is provided with spaced notches 38 and 38^a to receive the roller 37, said notches being of sufficient depth to allow the movable contact member 32 to open the circuit through the lock releasing magnet. These notches 38 and 38^a are so spaced that the roller 37 is positioned therein when the locking plunger P is in its extreme positions. The locking plunger P, even though the lock bolt B is in its lower position, may be moved a short distance to bring the roller 37 out of the notch, and thereby close the contacts and permit the lock releasing magnet M to be energized if the circuit is otherwise completed. When the locking plunger P is moved to either extreme position, the roller 37 drops in one of the notches 38 and opens the contacts to break the circuit through the lock releasing magnet M, thereby economizing in the energy used for releasing the lock.

In connection with the electric lock proper, embodying this invention, I also provide a simple circuit controller C of the rotary type, operated by the movement of the locking plunger. Since this circuit controller follows the movement of the lever, it can be used for governing the operation of power operated switches, signals, or the like, or may be used for selecting signal circuits, indication circuits, or for any other desired purpose. This controller comprises a shaft 39 supported in suitable bearing brackets fastened to the main frame or casing, and on the shaft are interchangeably mounted a plurality of drum sections 40 of insulating material having conducting segments 41 attached thereto. These drum sections are adjustably secured to the shaft in any suitable or well-known manner, so that they may be positioned with respect to the shaft to close or open the circuit at any predetermined position of the shaft. The drum sections are manufactured with different length of segments; and by using drum sections having contact segments of the desired length and by adjusting these sections about the shaft, a controller for every application of the electric lock may be built up with a very few number of different parts. Adjacent to and extending underneath the drum is a terminal board 42 of insulating material provided with two or more spring contact fingers 43 for each drum section, so that the contact segments may bridge their respective pairs of contact fingers.

The end of the shaft 39 remote from the lock releasing magnet M is provided with a crank 44 to which is pivotally connected a connecting rod 45, which has its other end pivotally connected to a U-shaped operating slide 46 which rides in recesses similar to those of the lock bolt B. This operating slide 46 straddles the locking plunger P and is provided with a pin carrying a roller 47

arranged to follow a cam slot 48 cut into said plunger, thereby causing the circuit controller drum to be turned at times during the movement of the plunger P, depending on the particular shape of the cam slot 48.

This lock and its mechanism is entirely enclosed by a hood comprising suitable arched end castings 49 connected together by sheet iron 49^a or the like, one of said castings being notched to provide clearance for the conduit outlet 50¹. This hood fits over the base and is held thereto by suitable fastening means, such as the hasp 50 and staple 51 shown.

When direct current is used for the lock releasing magnet M, the construction shown in Figs. 9 and 10 may be employed. In this construction the angle lever 20 is provided near the ends of the upwardly extending arms with a soft iron armature 52. Operating with the armature 52 is a pair of cores 53 mounted on the angle bracket 54, which is supported on the main frame or casing, and each of these cores is provided with a magnet coil 55. The two types of lock releasing magnets have interchangeable attaching means and one may be substituted for the other at any time if desired.

Fig. 2 illustrates in a diagrammatic way the principal operating parts of the lock, and shows it used as a track circuit controlled detector lock. Used in this way, the lock prevents movement of the lever when the detector track circuit, associated with the switch operated by that lever, is occupied. The well-known detector track circuit is shown conventionally and comprises a track battery 56 connected across the rails near one end of the track section, and a track relay Y connected across the rails at the opposite end of the track section, so that the relay Y is shunted out by a train on the track section, thereby causing the armature of the relay to drop and open the circuit through the front contact 57. The coils 29 of the lock releasing magnet M are connected in a circuit energized from a suitable source of current (illustrated as a transformer T, since the particular construction of the magnet shown is one specially designed to be operated by alternating current). This circuit, which may be readily traced on the drawing, includes a front contact 57 of the track relay Y, and the contacts 31 and 32 of the energy saving cut-out switch ES.

Assuming the locking plunger P to be in the normal position shown, as it is moved to the right toward the reverse position, it may only be moved a short distance until the dog 18 engages the lock bolt B. The roller 37 is raised from the notch 38 by this primary movement, causing the energy sav-

ing switch ES to be closed; and if the track circuit is not occupied, the energizing circuit for the lock releasing magnet M will be established. When this magnet is energized, the Z-armature 27 will be attracted, thereby rocking the angle lever 20 and raising the lock bolt B up so that the locking plunger P can be moved to its extreme reverse position. When the plunger P nearly reaches its reverse position, the guide cam 19 with its inclined or beveled end engages the upper edge of the lock bolt B, forcing it down behind the dog 18 in position to lock the plunger P against return movement; also, the energy saving switch 32 will again be opened by the roller 37, riding into the other notch 38^a when the plunger is shifted to its full reverse position. If the track circuit should be occupied, the lock releasing magnet M will not be energized, and the plunger P can not be moved beyond the point where the dog 18 engages the lock bolt B. When the lever is moved in the opposite direction, the operation is similar, and its description is not thought necessary. Since the lock bolt B is positively forced into position to engage the dog by the guide cam 19 each time the plunger P is shifted, proper locking of the plunger is assured regardless of friction between the parts. This feature not only makes the lock more positive and reliable in its performance, but also permits the lock to be mounted vertically or in an inclined position as conditions require.

While the lock embodying the invention is shown in Fig. 2, as controlled by a detector track circuit, it may be controlled by one or more track circuits to provide the desired control of the lock for route or approach locking, or for any other suitable form of track circuit controlled locking. Also, direct current may be used for operating the locks, as well as alternating current, but it is preferred to use the form of lock releasing magnet shown in Figs. 9 and 10 if direct current is used.

The lock embodying the invention may also be used as either a normal or reverse indication lock, or both, by arranging and proportioning the parts so that the engagement of the lock dog with the lock bolt B occurs at the desired position in the movement of the locking plunger P. If the indication current is given by a battery, or other source of supply, so that it continues to flow through the lock releasing magnet M until the lever L is operated to take advantage of the indication release, either the alternating current or direct current type of releasing magnets may be employed.

When it is desired to use the lock with a signal lever as an indication lock for the normal position of the lever, the guide cam 19^a is formed as shown in Fig. 14. Fig. 14

shows the plunger P in the reverse position, corresponding to the clear position of the signal. When the lever is shifted to put the signal in the normal or stop position, the plunger P moves to the right, as viewed in Fig. 14, to the point where the dog 18^a engages the lock bolt B. This prevents the signal lever L from being moved further to release the mechanical interlocking until the lock releasing magnet M is energized to raise the bolt B clear of the dog 18^a. If the signal coupled to the lever in question has properly responded and assumed its step position, the indication current supplied from any suitable source over any one of the well-known types or forms of indication circuits, by energizing the lock releasing magnet M, raises the bolt B and allows the movement of the lever to be completed, whereupon the parts assume the position shown in Fig. 15. If the lock is to be used with a switch lever as an indication lock, for both the normal and reverse positions of the lever, the guide cam is also provided at its opposite end with the beveled cam edge to force the lock bolt to its locked position.

Figs. 11 to 13 illustrate a modified construction of the lock dog by which the electric lock is adapted for use as an indication lock in dynamic indication systems. In a dynamic indication system, the indication current, usually generated by the rotation of the operating motor, flows only momentarily; and in order that the operator may take advantage of this indication current at any convenient time, after it has been received, it is desirable to provide a latch or detent device for holding the lock bolt in its unlocked position after once unlocked by the indication current. In the particular construction illustrated, the lock dog 59 is provided with a longitudinal recess 60 in which a latch or detent 61 is slidably supported. This latch 61 is provided with a longitudinal slot in which is a pin 62 fastened to the dog 59. The latch 61 is also bored lengthwise to form a housing for a long coiled compression spring 63, having one end engaging an end of the slot, and the other end engaging the latch guiding pin 62, thereby forcing the latch or detent 61 outwardly to the position shown in Figs. 11 and 12.

The particular arrangement shown in Fig. 11 is intended to be used in connection with a signal lever, the parts being shown in the position corresponding to the reverse position of the signal lever. When the lever is shifted toward the normal indication position, the plunger is moved to the right until arrested by the engagement of the dog 59 with the bolt B, the latch 61 being forced inward against the opposition of the spring 63. With the lever L in this normal indi-

cation position, power is applied to the signal, either electrically by the operation of the circuit controller C, or in any other suitable way. If the signal mechanism operates 5 properly, and the signal assumes the normal or stop position, the indication current generated dynamically at the completion of the operating cycle of the mechanism, energizes the lock releasing magnet M and raises the 10 bolt B so that the latch 61 may slip under the bolt B and hold it in the raised position. The end of the latch 61 is beveled so that it may move under the lock bolt B although the bolt is not raised to its highest 15 position. The plunger P is now unlocked, and the lever L connected to it may be moved at any subsequent time to the full normal position. When the lever L is subsequently put back to its reverse position, 20 the beveled end of the guide cam 19¹ forces the lock bolt B down to the position shown, ready for the next movement of the lever to its normal position. Obviously, the same modified construction of the lock dog may 25 be employed to provide indication locking for both the normal and reverse positions of the lever. In this discussion no particular form of power control of the signal or switch has been considered, since this may 30 take any one of the well-known forms.

In Fig. 16, provision is made so that the lock may be used, both, as a track circuit controlled lock and as an indication lock. The locking plunger P in this instance is 35 connected to any well-known form of lever, such, for instance, as shown in Fig. 1, which controls the electric switch machine SM, presumably a part of an otherwise mechanical interlocking plant. The plunger is provided with two dogs 59¹ and 59² like the one shown in Fig. 11, having their spring 40 pressed latches 61¹ and 61² facing each other. The guide cam 19² is similar to the ones already described, but also has an intermediate beveled projection 64 to force the lock bolt down when the plunger P moves to 45 its intermediate or indicating positions, the same as the beveled edges 98 at the end of the guide cam 19² force the lock bolt down in the extreme normal and reverse positions 50 of the plunger. The plunger P is provided with a long cam slot 48² arranged in four steps, corresponding to the four positions of the plunger, namely, normal, normal indication, reverse indication and reverse; and the 55 roller 47 in these four positions (indicated by the reference characters n, ni, ri, and r, respectively) shifts the controller drum to four corresponding positions.

60 The general organization of the typical system illustrated in Fig. 16 comprises an electrically operated switch machine SM, shown diagrammatically and comprising a series motor provided with a controller 65 which changes the connection of the arma-

ture 65 with respect to the field 66 and also the connection of the armature 65 from reverse operating wire R to the normal wire N, or vice versa, as the case may be, when the switch has been operated; a detector track 70 circuit (the relay Y only being shown); a circuit controller C operatively connected to the locking plunger; a lock releasing magnet with its energy saving switch ES, and a battery. 75

Assuming the switch and lever L to be in the normal position, the parts are in the position shown in Fig. 16, the plunger P being in its extreme left or normal position, with the roller 37 of the energy saving 80 device ES resting in one of the notches (not shown). When the operator desires to reverse the switch, he shifts the lever, slightly moving the locking plunger P to the right to the point where the dog 59¹ engages the lock bolt B and prevents further operation of the plunger P until the bolt is released. During this movement the roller 37 of the 85 energy saving device is moved out of the notch closing the energy saving switch 32. 90 During this movement the circuit controller drum 67 is not moved from its initial position. If the track circuit (not shown) adjacent to switch is not occupied, the track relay Y is energized, and the lock releasing 95 magnet M is energized by a circuit which may be traced from the battery 68, wire 81, through the front contact 57 of the track relay Y, wire 69, contact finger 70, drum segment 71, contact finger 72, wire 73, contact finger 74, wire 75, lock releasing magnet M, wire 76, energy saving switch 32, stationary contact 31, wire 77, wire 78, and back to the battery 68. Current flowing 100 through this circuit will raise the lock bolt 105 B permitting the locking plunger P to be moved to the right until the dog 59² engages the lock bolt B and compresses the spring of the latch or detent 61² of the dog 59², but preventing further movement of 110 the locking plunger.

During this movement, the roller 47 in the cam slot will have moved to the position marked ri in the cam slot 48², and the circuit controlled drum 67 will have moved 115 in the direction of the arrow so that the contacts 79 and 80 bridge their respective contact fingers. This will complete a circuit for operating the switch machine motor, which may be traced as follows:— 120 starting at the battery 68, through the feed wire 81, contact finger 82, contact segment 80, contact finger 83, wire R, terminal 84, movable contact 85, terminal 86, terminal 87, motor armature 65, terminal 88, terminal 89, movable contact 90, terminal 91, wire 92, field winding 66, wire 77, wire 78, and back to the battery 68. This circuit will 125 allow current to flow through the motor of the switch machine SM to throw the switch 130

into the opposite position; and when this operation has been completed, the movable contacts 85 and 90 will be thrown to bridge the terminals 93 and 88, and 87 and 94, respectively. The switch machine controller is now positioned to establish an indication circuit which may be traced as follows:— starting with the armature of the motor to the terminal 88, movable contact 85, terminal 93, wire N, contact finger 95, controller segment 79, contact finger 96, wire 97, wire 75, lock releasing magnet M, wire 76, energy saving switch 32, stationary contact 31, common return wire 77, motor field 66, terminal 94, movable contact 90, terminal 87, and back to the armature.

The armature 65 of the motor is rotating due to its acquired momentum, and when the indication circuit just traced is established 20 with the armature and field connections reversed, the residual magnetism in the field causes the motor to act as a series generator and produce a temporary flow of indication current, continuing so long as the armature of the motor is rotating. This current flowing through the circuit just traced, energizes the lock releasing magnet M and draws the lock bolt B up, causing the latch 61² to slip under the bolt, and hold it in 25 raised position. The lever L may now be shifted to the full reverse position, actuating the mechanical locking in the usual way to release other associated levers.

When the locking plunger P is moved to 30 its extreme right-hand position, the beveled edge 98 of the guide cam 19² will force the lock bolt B down into its locked position, and the roller 37 of the energy saving device will be positioned in the other notch 40 (not shown) provided in the locking plunger, thereby opening the switch of the energy saving device ES. When the locking plunger P is in this position, the contact segment 99 (shown in dotted lines) will 45 bridge the contact fingers 70 and 72, thereby placing the lock releasing circuit in condition for moving the locking plunger from the reverse to the normal position.

From the foregoing, it will be observed, 50 that in the normal and the reverse positions of the locking plunger P, the front contact 57 of the track relay Y will be connected in series with the lock releasing magnet M, the energy saving switch 32, battery 68, 55 while in either of the other positions the front contact 57 of the track relay Y is not connected in any circuit as is apparent from the drawing. When the locking plunger P is in either of its intermediate 60 positions, that is, the normal indication or reverse indication, the lock releasing magnet will be connected to the particular wire N or R, over which the dynamic indication current will be received.

65 It will be noted that in moving from the

normal position to the reverse indication position, the controller drum 67 passes through the position in which the contact segments 100 and 101 bridge their respective contact fingers, but no current will flow 70 during such time because the circuit established has no source of current in it.

The operation of this device from the reverse to the normal position is substantially the same as the one just described.

The electric lock forming the subject matter of this application has a very wide application in railway signaling. It is interchangeably constructed so that it may readily be applied to any one of the various 80 uses hereinbefore enumerated. The interchangeable features summed up briefly, consist of a two-part housing with the necessary recesses, which is easily assembled and disassembled to facilitate interchanging the various locking plungers; a lock bolt, controller mounting, controller operating mechanism, energy saving device and cover which constitutes the basic mechanism for the lock. This basic mechanism is adapted 85 to receive any one of the various locking plungers, a built-up controller drum to suit the particular circumstances in serving as a signal circuit selector, a controller for distant traffic controlling mechanism, or both 90 as hereinbefore pointed out, and the particular electric lock releasing mechanism operable as the source of current available. Therefore, by having the basic lock mechanism and each of the interchangeable parts 100 in stock, the consumer would be equipped to meet any one of the various problems which he may expect to encounter, without a great deal of expense in stocked parts; and likewise the manufacturer need not be stocked up so heavily in the various distribution centers, to meet the demands of 105 his customers.

While several specific embodiments of the invention have been shown and described, together with different organizations or combinations of parts to adapt the lock to various uses, it should be understood that these specific constructions are merely illustrative, and that various other adaptations and modifications can be made without departing from the invention.

What I claim is:—

1. An electric lock for mechanical levers, comprising, a casing made up of two counter-part halves bolted together to form a longitudinal recess, a locking plunger guided in said recess having a shoulder, a U-shaped lock bolt straddling said locking plunger to engage said shoulder and slidably mounted in said casing, and means to raise said lock bolt to unlock said plunger.
2. An electric lock for mechanical levers comprising, a slidable locking plunger, a dog fastened to the plunger, a U-shaped lock

bolt straddling the plunger and rigidly guided for movement substantially at right angles to the direction of the movement of the plunger, and an energy saving contact controlled by said plunger.

3. In an electric lock for mechanical levers, a slideable plunger directly connected to the lever, a casing made up of two counter-part members fastened together and 10 guiding said plunger, and a lock bolt supported and guided by said members of the casing for cooperating with the plunger.

4. An electric lock for mechanical levers comprising, a two-part casing, a slideable 15 plunger guided by the casing, a dog fastened to the plunger, a bolt for engaging the dog, a unitary electro-responsive device detachably fastened to the two parts of the casing, and means operatively connecting the bolt 20 and the electro-responsive device.

5. An electric lock for mechanical levers comprising a lock bolt, an angle lever connected to the bolt, and electro-magnetic means having a Z-armature for rocking the 25 angle lever.

6. An electric lock for mechanical levers, comprising a casing, a locking plunger slideably mounted in said casing and having a shoulder, a lock bolt for engaging said 30 shoulder, and a double angle lever pivotally supported and straddling said shoulder, said angle lever having one pair of arms pivotally attached to said lock bolt, and means for operating the angle lever to raise the bolt 35 out of its locked position.

7. An electric lock for mechanical levers comprising, two counter-part members bolted together to form a recessed casing to receive the locking mechanism, a conduit 40 outlet attached to the counter-part members at one end of the casing, and a hood extending over said casing to protect the mechanism.

8. The combination of a lever of a mechanical interlocking plant for railways, an electric lock comprising a locking member 45 having a cutaway portion and connected directly to said lever, a lock dog fastened in said cutaway portion, a lock bolt cooperating with said lock dog to hold the same in locked position, said member and bolt being of sufficient strength to withstand the force that can be applied thereto by the lever.

55 9. In an electric lock for the levers of mechanical interlocking machines having lever locking comprising, a slideable locking plunger having a cutaway portion, a lock dog detachably mounted in said cutaway portion, a lock bolt arranged to engage said lock dog, and means associated with said plunger for forcing said lock bolt into engagement with said lock dog.

60 10. An electric lock for mechanical levers, comprising a locking member having a por-

tion thereof cut away, a lock dog screw fastened in said cutaway portion, a lock bolt for engaging said lock dog, electro-responsive means for releasing said lock bolt, and a retainer anchored at both ends to the 70 plunger and extending over said lock bolt to force it into locking position.

11. An electric lock for mechanical levers comprising, a slideable plunger directly connected to the lever and provided with a locking shoulder, a U-shaped bolt straddling the plunger and adapted to engage said shoulder, and a guide cam fastened to the plunger and acting to force the bolt into 75 position to engage the shoulder as the plunger is shifted.

12. An electric lock comprising, a slideable locking plunger provided with a dog, a lock bolt to engage said dog, and a spring pressed 80 detent projecting from the end of said dog to hold the lock bolt in raised position, so that the locking plunger may be moved at any time after the lock bolt has been raised.

13. An electric lock for mechanical levers, comprising a slideable locking plunger having locking shoulders, a lock bolt adapted to engage either of said shoulders, electro-responsive means for releasing said lock bolt, and a spring-pressed detent projecting from one of said shoulders, said spring-pressed 90 detent being adapted to maintain the dog out of engagement with the corresponding shoulder after such disengagement has been effected.

14. In an electric lock, a plunger, a dog fastened to the plunger, a detent associated with the dog, and spring means for projecting 95 said detent from one end of the dog.

15. In an electric lock, the combination with a slideable plunger and a lock dog fastened thereto, a bolt for engaging one end of the dog, and means supported and guided by the dog for holding the bolt out of engagement therewith when such disengagement has been effected.

16. An electric lock for switch levers, a slideable locking plunger having a plurality of locking shoulders, a spring detent for each shoulder, a lock bolt arranged to engage said shoulders, an electro-magnet for releasing said lock bolt, dynamic indication means for energizing said magnet, and a guide cam for forcing said lock bolt in position to engage one of said shoulders in 115 each of its locked positions.

17. An electric lock for signal levers, a slideable locking plunger having a locking shoulder, a spring detent for said shoulder, a lock bolt arranged to engage said shoulder, an electromagnet for releasing said lock bolt, dynamic indication means for energizing said magnet and a guide cam for forcing said lock bolt in position to engage 125 said shoulder.

18. An oblong lever lock comprising, a casing, a plunger guided lengthwise in the casing, a bolt for locking the plunger, electro-magnetic means at one end of the casing for releasing the bolt, and circuit controlling means at the other end of the casing operated by the plunger comprising, a horizontally disposed drum, a vertically movable link for operating said drum, and a roller contained in a slot in said plunger for operating said link.

19. An electric lock for mechanical levers, comprising a casing, a locking plunger slidably supported in said casing, and provided with shoulders, a lock bolt for engaging said shoulders, a cam slot in one end of said plunger, a circuit controller supported over said cam slot and operated thereby, and an electro-responsive means mounted over the other end of the casing and adjacent said controller for releasing said lock bolt.

20. A lever lock comprising, a plunger, a bolt for locking said plunger in any one of various positions, a casing for supporting and guiding the plunger and bolt, electro-magnetic lock releasing means for releasing said lock attached to the casing near one end thereof, a circuit controller operated by the plunger and attached to the casing near its opposite end, and a protecting hood for said parts.

21. An electric lock for mechanical levers, comprising a casing, a locking plunger slidably mounted in said casing and having a shoulder, a lock bolt to engage said shoulder, an electro-responsive device attached to the casing over the plunger near one end of the casing, a circuit controller disposed lengthwise over the plunger and attached to the casing near its other end, and an angle lever having one arm extending between the controller and plunger and attached to said lock bolt, the other end of said lever extending between said electro-responsive device and controller, and actuated by said electro-responsive device to raise the lock bolt and thereby release said plunger.

22. In an electric lock for the levers of mechanical interlocking machines having lever locking, comprising, a locking plunger having a locking shoulder, a lock bolt arranged to engage said shoulder, electro-magnetic means for releasing said lock bolt, and an energy saving device actuated by said plunger to cut off the energy from said means at a predetermined position of the plunger.

23. An electric lock for mechanical levers, a casing, a locking member supported in said casing having a deformed portion and a shoulder, a lock bolt arranged to engage said shoulder, electro-responsive means to raise said lock bolt, an energy saving device comprising a switch, and means for

operating said switch provided with a roller riding on said locking member and adapted to engage said deformed portion to open the circuit to said electro-responsive device when the lever is in one of its extreme positions.

24. In an electric lock having a locking plunger and an electro-magnetic lock releasing means, means operated automatically by the movement of the plunger for governing the supply of current to said means.

25. An electric lever lock having a movable locking element and electro-magnetic releasing means therefor, an energizing circuit for the means, and automatic means operated by the movement of said locking element for opening and closing said circuit.

26. In an interlocking system, the combination with a lever, a locking plunger connected to said lever, a controller drum rotated intermittently by a continuous movement of the plunger, a lock for said plunger, and electrical means for releasing said lock.

27. The combination of a lever of a mechanical interlocking plant for railways provided with means for operating a distant traffic controlling device mechanically, an electric lock connected directly to said lever, comprising a slidable locking plunger, a lock bolt for locking said plunger, electro-responsive means for releasing said lock bolt, and a circuit controller operated directly by said plunger for cutting energy off of said electro-responsive means in certain positions of said plunger.

28. An electric lever lock comprising, a plunger having a cam slot therein, a rotary circuit controller, and means cooperating with said cam slot for operating the circuit controller in accordance with the movement of the plunger.

29. In a mechanical interlocking plant for operating traffic controlling devices, a plurality of levers, one of said levers being provided with means for operating a distant traffic controlling device electrically, a lock connected directly to said lever, electro-responsive means for releasing said lock, and a controller operated directly by said lock for controlling said distant traffic controlling device.

30. In a mechanical interlocking plant for operating switches and signals mechanically, an electric lock including a locking plunger operatively connected directly to one of said levers, a lock for said plunger, a controller operated directly by said plunger for controlling a distant traffic controlling device, and indication means to release said lock after the distant traffic controlling device has been operated.

31. In a mechanical interlocking plant for operating traffic controlling devices, a

- plurality of levers, one of said levers being provided with an electric lock connected directly thereto, said lock comprising a locking member having a shoulder, a lock bolt arranged to engage said shoulder, an electro-responsive means for releasing said bolt, and a track circuit controlled relay for controlling said electro-responsive device. 32. The combination of a lever of a mechanical interlocking plant for railways, an electric lock connected directly to said lever, and comprising a slidable locking plunger, a lock bolt for locking said plunger, electro-responsive means for releasing said lock bolt, a distant traffic controlling device, a plurality of circuits for controlling the electro-responsive means, and a controller operated directly by said plunger for alternately connecting said electro-responsive means to said circuits and for controlling said distant device. 33. The combination of a lever of a mechanical interlocking plant for railways, an electric lock connected directly to said lever and comprising a slidable locking plunger, a lock bolt for locking said plunger, electro-responsive means for releasing said lock bolt, a plurality of circuits for actuating said electro-responsive means, a distant power operated traffic controlling device; and a controller operated directly by said plunger for alternately connecting said electro-responsive means to said circuits and for controlling said distant traffic controlling device. 34. In an interlocking system, the combination with a lever, a locking plunger connected to said lever, a lock for said plunger, electro-responsive means for releasing said lock, a circuit adapted to be connected to a continuously present source of potential, a dynamic indication circuit, and a circuit controller operatively connected to said plunger for alternately connecting said circuits to said electro-responsive means in the different positions of the plunger. 35. An electric lock for the levers of mechanical interlocking machines having lever locking comprising a slidable locking plunger provided with shoulders for locking the plunger in four different positions, a lock bolt arranged to engage said shoulders, electro-responsive means for releasing said lock bolt, and a controller for said responsive means operated intermittently four successive times by the continuous movement of said plunger from one to the other of its extreme position. 36. An electric lock for the levers of mechanical interlocking machines having lever locking comprising means provided with shoulders to lock said lever in four different positions, a lock arranged to engage said shoulders, a controller having four operative positions operatively connected to said means, and a guide cam associated with said means for forcing said lock into engagement with each of said shoulders. 37. An electric lock for mechanical levers comprising, a locking member having shoulders, a lock bolt for engaging said shoulders, electro-magnetic means for releasing said lock bolt, a track circuit, a relay, a circuit governed by said relay and including a source of energy for controlling said magnet, a power operated traffic controlling device having indication circuits, and means for alternately connecting said circuits to said electro-magnetic means in the several locked positions of the plunger. 38. An electric lock for mechanical levers comprising, a locking member having shoulders, a lock bolt for engaging said shoulders, a magnet for releasing said lock bolt, a track circuit controlled circuit, dynamic indication circuits, and a circuit controller operatively connected to said locking member for connecting either a dynamic indication circuit or a track circuit controlled circuit to said magnet in the several locking positions of the member. 39. In combination, an electric lock comprising a locking member having shoulders and directly connected to a lever of an interlocking machine, a lock for engaging said shoulders, an electro-responsive device for raising said lock, a track circuit, a relay in said track circuit, a circuit controlled by said relay and including a source of energy for controlling said electro-responsive device, a distant traffic controlling device having indication circuits for also controlling said electro-responsive device, and a controller for operating said traffic controlling device and also for alternately connecting one circuit and then the other circuit to said electro-responsive device. 40. An electric lock comprising, a locking member, having normal and reverse locking positions and an indication position, a shoulder on said member for each of said positions, a latch for engaging said shoulders, an electro-responsive device for operating said latch, a dynamic indication circuit, another indication circuit which is track relay-controlled, and a circuit controller operated by said member for alternately connecting the dynamic indication circuit and said another indication circuit to said electro-responsive device. 41. An electric lock comprising, a locking member having normal and reverse locking positions and indication positions, a shoulder for each of said positions, the shoulders of said indication positions being provided with detents, track relay controlled circuits including a source of energy, dynamic indication circuits, and a controller operated

- by said member for selecting the proper circuit for each of said locking positions.
42. An interchangeable electric lock comprising, a casing provided with a recess, a lock bolt, a locking plunger adapted to have attached thereto dogs and guide cams of various configurations and adapted to slide in said recess, a movable member connected to said bolt, electro-responsive devices adapted to be operated on various sources of energy supply and constructed to be attached to said casing for actuating said movable member, a circuit controller having a drum comprising a plurality of adjustable and interchangeable sections, and means for operating said circuit controller by the locking plunger.
43. In a mechanical interlocking plant for operating railway traffic controlling devices, the combination of a lever, an electric lock for locking said lever comprising a casing, a locking plunger in said casing mechanically connected to said lever, electro-magnetically released means for locking the plunger, an energy saving switch in the energizing circuit of said electro-magnetic means, and means operated by initial movement of said locking plunger for operating said energy saving switch.
44. An electric lock for levers of mechanical interlocking plants for railways adapted to be operatively connected to a lever by a single connecting link and including electro-magnetic means which if de-energized will lock said lever, and means for cutting energy off of said electro-magnetic means when said link is in either of its extreme positions.
45. In a mechanical interlocking plant for operating switches and signals from a distance mechanically, the combination with a plurality of levers, of a connecting link connected to one of said levers, and means connected to said link for controlling a distant traffic controlling device electrically comprising, a locking plunger, electro-magnetic means for locking said plunger if de-energized, an energy saving switch connected in series with said electro-magnetic means, and a circuit controller actuated in accordance with the movement of said plunger for operating said distant traffic controlling device.
46. In an electric lock, the combination of two counterpart members which if assembled form a casing having a recess, of a locking plunger having a portion thereof cut away to form a notch and slidably supported in said recess, a lock dog detachably fastened in the notch of said plunger, a lock bolt adapted to be engaged by said dog to prevent further movement of said dog, and means detachably connected to said plunger for forcing said lock bolt to its operative position.
47. An electric lock for locking levers of railway traffic controlling devices comprising, a casing having a recess, a locking plunger slidably supported in said recess and provided with a deformed portion, a shoulder on said plunger, a lock bolt cooperating with said shoulder, electro-magnetic means for actuating the lock bolt, and means adapted to cooperate with the deformed portion of said plunger for at times cutting energy from said electro-magnetic means.
48. An electric lock for railway traffic controlling appliances comprising, a locking plunger having a recess and a locking shoulder, a lock bolt for cooperating with the locking shoulder, electro-magnetic means for actuating said lock bolt, and an energy saving switch connected in series with said electro-magnetic means and including an operating arm provided with a roller adapted to ride on said locking plunger and move into said recess.
49. An electric lock for railway traffic controlling appliances comprising, a locking plunger having a cam slot and a locking shoulder, an electrically operated lock bolt cooperating with said shoulder, a drum-type circuit controller, a slide member supported for movement transversely to the movement of the plunger, a roller carried by said member and disposed in the cam slot of the plunger, and means for causing rotary movement of said circuit controller by transverse movement of said slide member.
50. An electric lock for railway traffic controlling devices comprising two counter-part members bolted together to form a recessed casing, a locking plunger slidably supported in the recess of said casing and having a locking shoulder, a lock bolt slidably supported for movement transverse to the movement of the locking plunger, a guide cam fastened to said locking plunger for actuating said lock bolt to its active position upon movement of the locking plunger to its locked position, and means fastened to opposite sides of said lock bolt for actuating said lock bolt to the unlocked position.
51. An electric lock for railway traffic controlling devices comprising, a locking plunger having a locking shoulder, a U-shaped lock bolt slidably supported for movement transversely to the movement of the plunger and adapted to have the closed end thereof engage the locking shoulder, a guide cam fastened to said locking plunger for actuating said lock bolt to its locking position upon movement of the locking plunger to its locked position, and means fastened to opposite sides of said U-shaped lock bolt for actuating said lock bolt to the unlocked position.
52. An electric lock for railway traffic controlling devices comprising, a locking plunger

er having a locking shoulder, a U-shaped lock bolt guided for movement transverse to the movement of the locking plunger and arranged to engage said shoulder, a guide 5 cam fastened to said locking plunger for actuating said lock bolt to its locking position upon movement of the locking plunger

to its locked position, and pivotally supported means having a pin and slot connection to said lock bolt for actuating the lock bolt to its unlocked position.

In testimony whereof I affix my signature.

JAMES E. STEPHENSON.
